UNITED STATES PATENT OFFICE

FREDERICK H. ROHR, OF SAN DIEGO, CALIFORNIA, ASSIGNOR TO SOLAR AIRCRAFT COMPANY, OF SAN DIEGO, CALIFORNIA, A CORPORATION OF DELAWARE

RIVETING MACHINE

Application filed June 6, 1929. Serial No. 368,975.

My invention relates to riveting machines, and the objects of my invention are: first, to provide a machine of this class which presses against rather than strikes the rivets, thereby reducing the danger of crystallization; second, to provide a machine of this class which, operating by pressure rather than impact causes the shank of the rivet to swell into and completely fill the hole through which it extends and enables the extended end of the shank to form a smooth head of any desired shape, thus the rivet is caused to firmly and tightly grip the work between its head; third, to provide a clamp means co-operating with the riveting means which holds the work firmly in place during the riveting operation; fourth, to provide a machine of this class which operates by fluid pressure; fifth, to provide a riveting machine which although capable of delivering the great pressure needed to press a rivet into shape is extremely compact, and which may be readily made in a portable form, if desired; sixth, to provide a riveting machine in which the riveting plunger and die may be readily removed for replacement or the like; seventh, to provide a riveting machine in which the vise or work clamping means may be readily disconnected or removed if desired to use the riveting mechanism alone; eighth, to provide a riveting machine in which only one movement of the riveting plunger is necessary in order to perform the riveting operation; ninth, to provide a riveting machine which is practically silent in operation; tenth, to provide a riveting machine in which the force upon the riveting plunger is automatically released if the plunger moves further than it is necessary for the riveting operation, thus should the device be operated without work between the plunger and die, the plunger will not engage the die with sufficient force to do harm; eleventh, to provide a riveting machine which may be readily constructed in various shapes so as to rivet in awkward or unusual places, and twelfth, to provide a riveting machine which is extremely simple of construction proportional to its functions, durable, efficient in its action, and which will

not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a longitudinal sectional view of my riveting machine taken through 1-1 of Fig. 5, with parts and portions shown in elevation to facilitate the illustration; Fig. 2 is a transverse sectional view thereof taken through 2-2 of Fig. 1, with parts and portions shown in elevation to facilitate the illustration; Fig. 3 is another longitudinal sectional view through 3-3 of Fig. 5, with parts and portions shown in elevation to facilitate the illustration; Fig. 4 is a sectional view through 4-4 of Fig. 1, with parts and portions shown in elevation to facilitate the illustration; Fig. 5 is a sectional view through 5-5 of Fig. 1, with parts and portions shown in elevation to facilitate the illustration; Fig. 6 is a transverse sectional view through 6-6 of Fig. 1, with parts and portions shown in elevation to facilitate the illustration; and Fig. 7 is a plan view of the plunger operating lever with one of the vise operating levers shown in relation thereto.

Similar characters of reference refer to similar parts and portions throughout the several views of the drawings.

Casing 1, riveting die member 2, stationary vise jaws 3, bushing 4, riveting plunger 5, riveting plunger spring 6, bushing 7, vise shank members 8, movable vise jaws 9, cap members 10, compensating springs 11, collars 12, springs 13, riveting lever 14, vise levers 15, sleeve members 16, shaft member 17, riveting plunger engaging roller 18, shank cap engaging rollers 19, riveting lever 20, vise lever cam rollers 21, cam member 22, cam guide rollers 23, cam guide roller pins 24, cylinder member 25, piston 26, cam supporting pin 27, sealing means 28, spring 29, and lid member 30, constitute the

principal parts and portions of my riveting machine.

The casing 1 comprises a base portion 1a joined to an apron portion 1b which extends 5 downwardly from the forward side of said base portion. The apron portion 1b supports a bracket portion 1c which extends upwardly and outwardly on the opposite side of the apron from the base portion 1a. The upper surface of the bracket portion 1c is provided with a channel 1d which extends transversely to the riveting machine.

The sides of the channel 1d are cut under so as to dovetail with the lower portion of a 15 die member 2 and the similar lower portions of two stationary vise jaws 3, one positioned on each side of the die member 2, as shown best in Fig. 5. The vise jaws 3 and die member 2 may be removed by sliding 20 them sideways out the end of the channel 1d.

The casing 1 is provided with a forward wall 1e which extends upwardly at the forward side of the base member 1a forming a continuation of the apron 1b. The forward 25 wall 1e curves forwardly at its upper portion and forms a head portion 1f. The head portion 1f is in vertical alinement with the bracket 1c, as shown best in Figs. 1 and 5. The head portion is provided with an opening 1g therethrough which is centered relative to the head portion 1f and in alinement with the die member 2, as shown best in Figs. 1 and 5. The opening 1g is constricted at its lower portion and receives a bushing 4.

Slidably mounted in the bushing 4 is a riveting plunger 5, the lower end of which is shaped in a manner suitable for forming a rivet head. The upper end of the riveting plunger 5 is enlarged so as to form a sliding 40 joint with the side walls of the opening 1g. Between the head or enlarged portion 5a of the riveting plunger and the bushing 4 is positioned a spring 6 which tends to hold the plunger out of engagement with its die 45 2. The head portion 1f is provided with two other openings 1h therethrough, one on each side of the opening 1g, and in parallel spaced relation thereto. The bottom portion of each opening 1h is constricted and receives a bush- 50 ing 7.

Slidably mounted in each bushing 7 is a vise shank member 8. Removably secured to the lower end of each vise shank member 8 is a movable vise jaw 9, which has a substantially flat lower side adapted to register with the stationary vise jaws 3. The movable vise jaws 9 extend as close as possible to the riveting plunger 5, as shown best in Fig. 5.

The upper end of each vise shank member 8 terminates in a head portion 8a over which fits the sleeve portion 10a of a cap member 10. The sleeve portion 10a of the cap member 10 forms a snug sliding fit with its opening 1h. Positioned between the head of each

vise shank member 8 and the closed end of its cap 10 is a compensating spring 11. Each spring 11 is relatively strong and adapted to permit slight relative movement of the cap and vise shank member 8.

A collar 12 fits on the under side of each vise shank head 8a and a spring 13 is positioned between each collar 12 and the corresponding bushing 7. These springs 13 are adapted to hold the movable jaw of the vise 75 out of engagement with the stationary jaw. The riveting plunger 5 is operated by a riveting lever 14, while the vise shank members 8 are operated by vise levers 15. One vise lever 15 is mounted on each side of the riveting lever 14. Bearing brackets 1j extend rearwardly from the head portion 1f on either side of the vise lever 15. The base member is provided with side walls 1k which extend upwardly therefrom until flush with 85 the upper side of the head member 1f. Bearing brackets 1m are formed in the side portions 1k in alinement with the bearing brackets 1j.

A sleeve or bearing member 16 extends 90 from each bearing bracket 1j to its nearest adjacent bearing bracket 1m and forms the pivoting axis for the vise levers 15, as shown best in Fig. 6. A shaft member 17 extends through the sleeve members 16 and supports 95 the riveting lever 14 between the bearing brackets 1j, as shown in Figs. 1 and 6.

The riveting lever 14 curves upwardly and forwardly from its pivoted portion and terminates in a forked end 14a positioned above 100 the riveting plunger, as shown best in Figs. 1 and 5. Rotatably mounted in the forked or bifurcated portion 14a by means of a pin 14b is a roller 18 which engages the upper end of the riveting plunger 5.

An arm of each vise lever 15 corresponding to the aforementioned arm of the riveting lever 14 extends upwardly to a position over the corresponding cap member 10 and terminates in a bifurcated portion 15a between the members of which by means of a pin 15b is journaled a roller 19 adapted to engage the upper end of the corresponding cap member 10.

The other arms 14c of the riveting lever 14 115 extends rearwardly and downwardly into the chamber formed by the base 1a, front wall 1b, the side walls 1k and a rear wall 1n extending upwardly from the rear side of the casing member 1. This rearwardly extending arm 14c of the riveting lever 14 terminates in a bifurcated portion 14d between the members of which a roller 20 is journaled by means of a pin 14e. Similarly the rearwardly and downwardly extending arm 15c 125 of each vise lever 15 terminates in a bifurcated portion 15d between the members of which a roller is journaled by means of a pin 15e, as shown best in Fig. 3.

The rollers 20 and 21 are adapted to engage 130

a cam member 22, as shown best in Figs. 1, 3, 4, and 6. The cam is in the form of a bar which extends rearwardly through an opening provided in the rear wall in which extends upwardly from the base portion 1a of the casing and joins the two side walls 1b thereof. The end of the cam engaged by the rollers is the extended end and is adapted to rest on a plurality of guide rollers 23 which are supported transversely to the cam between the side walls 1b of the casing on roller pins 24, as shown in Figs. 1, 3, 4 and 6. Bosses 1p extend inwardly from the side walls 1b of the casing 1 and engage the side margins of the cam so as to hold it in alignment with the rollers 20 and 21. The rollers 21 of the vise operating levers 15 engage the outer side margins of the cam, designated 22a, while the rollers 20 connected with the riveting lever 14 engage the central portion of the cam, designated 22b. The cam 22 is adapted to raise the arms 14c and 15c of the levers 14 and 15 by wedging between the guide rollers 23 and cam rollers 20 and 21, thereby causing the other arms of the levers 14 and 15 to depress the riveting plunger 5 or movable vise jaws 9, as the case may be.

Supported by the rear wall 1n of the casing 1 and extending rearwardly therefrom is a cylinder member 25 of annular cross section. The head of the cylinder is closed except for a small opening connected with a source of compressed air supply, or other fluid, not shown. Slidably mounted in the cylinder member 25 is a piston 26. The skirt 26a of the piston is provided with inwardly extending boss portions 26b which are hollow and receive a pin 27 adapted to support the end portion of the cam 22. The piston is provided with suitable sealing means 28, such as a cup leather. A spring 29 extends between the piston 26 and the secured end of the cylinder 25, as shown in Figs. 1 and 3, so as to cause the piston to return to the head of the cylinder when the air pressure is released.

The upper end of the casing or housing 1 is open but may have a hinged lid 30 to conceal the working parts and at the same time to permit ready access to the mechanism.

50 The shaft member 17 supporting the lever 14 has a relatively loose sliding fit in the sleeve members 16 so that the riveting operating lever 14 may be readily removed. As soon as the riveting lever 14 is removed 55 the riveting plunger 5 may be easily taken out of its casing and a new one inserted, if desired.

If desired, the sleeves 16 may have a loose 60 sliding fit with their journals so that they may be readily removed in order that the vise operating levers 15 may be taken out, thus rendering the vise inoperative or enabling the shank and other portions of the vise mechanism to be removed, thus enabling the rivet-

ing portion of the machine to operate without the aid of the vise mechanism.

The operation of my riveting machine is as follows: It is preferred to bring the vise portions of my riveting machine into operation before the riveting portions thereof. This is accomplished by increasing the height of the cam portions 22a which operate the moving vise jaws 9 before the cam portions 22b begins to raise. When the device is ready to begin operation, it is in the position shown by the solid lines in the several views, principally in Figs. 1 and 3. In this position the cam portions 22a are held in yieldable engagement with the rollers 21 by means of the spring 29 extending between the piston 26 and the head of the cylinder 25. The rollers 21 as before stated, are connected through their respective levers 15 to the vise jaws 9, as shown best in Fig. 3. The cam portions 22a curve upwardly rather abruptly from its forward end so that only slight movement of the piston is necessary to bring the vise jaws into contact with the work. The cam portion 22b is flat for a considerable distance before turning up forming a shelf portion 22c. This shelf portion is opposite the rising portion of the cam 22a and does not merge into the rising portion of the cam 22b until almost opposite the major portions of the cam 22a, as shown best in Figs. 1 and 3. The arm 14c being somewhat longer than the arms 15c is supported by its roller 20 upon the shelf 22c when the rollers 21 are in engagement with the ends of the cam. Air under pressure delivered into the space between the head of the cylinder and the head of the piston causes the cam to move forward, raising the levers 15 and causing the movable vise jaw to come in contact with the upper side of the work and clamp the work between said movable jaws and the stationary jaws of the vise. The compensating spring 11 absorbs whatever excess movement there is in the levers 15, thus preventing the device from locking and enable the vise jaws to hold either thick or thin work.

Further movement of the piston 26 and cam 22 causes the roller 20 of the plunger operating lever 14 to rise upon the cam portion 22b and depress the plunger 5. It is preferred to have the cam portion 22b curve rather abruptly at the point where it merges into the shelf 22c so that the first movement of the plunger is rather rapid. The slope of the cam 22b gradually decreases after its first more abrupt portion so that the plunger slows down as it comes in contact with the end of the rivet until when it has reached the point where force is needed to mash and reform the rivet the cam surface 22b is relatively flat and a considerable movement of the piston 26 is necessary in order to accomplish the slight movement of the plunger 5 necessary. Thus a tremendous amount of force can be applied to the end of the rivet so as to cause it to

swell out in the work through which it extends and spread out at its extended end so as to form second rivet head which firmly clamps the work between the previously formed head of the rivet.

5 By varying the shape of the cams 22a and 22b it is possible to have just the pressure and movement necessary to suit the particular kind of riveting done by the machine.

10 The spring 29 returns the piston to the head of its cylinder when the air pressure is released.

15 It is obvious that by substituting other tools or mechanism in place of the die member 2, stationary vise jaws 3, the plunger 5, vise shank members 8, and variable vise jaws 9, the machine may be used to shear, stamp, punch or perform other work.

20 In order to limit the downward movement of the riveting plunger 5 so that it will not strike the die member 2 when the work is between them, ports 25a may be provided in the side walls of the cylinder 25 at the proper place to by-path the air just before the 25 plunger strikes the die member, thus releasing the force behind the plunger, preventing injury to either the plunger or die member.

25 Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

40 1. In a riveting machine, a casing, a riveting plunger, a riveting die, lever means engageable with said plunger, and cam means engageable with said lever, a cylinder connected with the said casing and receiving an end of said cam means, a fluid actuated piston therein connected to said cam means, said piston adapted to force a portion of said cam means into engagement with said lever, independently operable vise means 45 mounted adjacent to said plunger for holding the work acted upon by said plunger and vise operating lever means for actuating said vise means, said vise lever means engageable by another portion of said cam.

55 2. In a riveting machine, a cylinder, a piston slidably mounted therein, a sliding cam connected with the said piston, a lever engageable by said cam, a riveting plunger engageable by said lever, independently operable vise means having fixed and movable jaws mounted adjacent to said structure for holding the work acted upon by said riveting plunger, and vise operating lever means 60 for actuating the movable jaws of said vice

means, said vise lever means engageable by said cam.

3. In a riveting machine, a cylinder, a piston slidably mounted therein, a cam connected with the said piston, guide means for said cam, a lever, one portion thereof movable into close proximity to said guide means, a riveting plunger connected with another portion of said lever, said cam adapted to wedge between said lever and guide means, and cause movement of said lever, independently operable vise means mounted adjacent to said riveting plunger for holding the work acted upon by said structure, and vise operating lever means for actuating said vise means, said vise lever means engageable by said cam.

4. In a riveting machine, a cylinder, a piston slidably mounted therein, a sliding cam connected with the said piston, a lever engageable by said cam, a riveting plunger engageable by said lever, other cam means connected with said piston, other lever means engageable with said other cam means, a vise means, movable jaws therefor actuated by said other lever means, and located adjacent to said riveting plunger so as to hold the work acted upon by said plunger.

5. In a riveting machine, a cylinder, a piston slidably mounted therein, a sliding cam connected with the said piston, a lever engageable by said cam, a riveting plunger engageable by said lever, other cam means connected with said piston, other lever means engageable with said other cam means, a vise means and movable jaws therefor actuated by said other lever means, and located adjacent to said riveting plunger so as to hold the work acted upon by said plunger, said other cam means shaped so as to bring said vise means into action before said first cam brings said riveting structure into action.

6. In a riveting machine, a cylinder, a piston slidably mounted therein, a sliding cam connected with the said piston, a lever engageable by said cam, a riveting plunger engageable by said lever, other cam means connected with said piston, other lever means engageable with said other cam means, a vise means, movable jaws therefor actuated by said other lever means, and located adjacent to said riveting plunger so as to hold the work acted upon by said plunger, said other cam means shaped so as to bring said vise means into action before said first cam brings said riveting structure into action, and resilient means associated with said movable vise jaws for taking up the extra movement of said other cam after said vise has engaged in the work.

7. In a riveting machine, a cylinder, a piston slidably mounted therein, a cam connected with the said piston, guide means for said cam, a lever, the one portion thereof adjacent to said guide means, a riveting plunger

er connected with another portion of said lever, said cam adapted to wedge between said lever and guide means, and cause movement of said lever, other sliding cam means adapted to ride on said guide means, other lever means having one portion thereof adjacent to said guide means, a vise means for holding work to be acted upon by said riveting plunger, and movable jaws therefor engageable with said other lever means, said other sliding cam means adapted to wedge between said guide means and said other lever means and cause movement of said other lever means, so as to actuate said movable jaws.

8. In a riveting machine, a cylinder, a piston slidably mounted therein, a cam connected with the said piston, guide means for said cam, a lever, one portion thereof adjacent to said guide means, a riveting plunger connected with another portion of said lever, said cam adapted to wedge between said lever and guide means, and cause movement of said lever, other sliding cam means adapted to ride on said guide means, other lever means having one portion adjacent to said guide means, a vise means for holding work to be acted upon by said riveting plunger, and movable jaws therefor engageable with said other lever means, said other sliding cam means adapted to wedge between said guide means and said other lever means, and cause movement of said other lever means, so as to actuate said movable vise jaws, said vise jaw actuating means comprising said vise, cam and lever means constructed so as to bring said vise means into action before said riveting plunger is brought into action, so that the force delivered to said riveting plunger is increased as said plunger is brought into action, until when it is in actual engagement with a rivet, sufficient force is developed to enable said riveting plunger to shape said rivet by a pressing action.

9. In a riveting machine, a cylinder, a piston slidably mounted therein, a cam connected with the said piston, guide means for said cam, a lever, one portion thereof adjacent to said guide means, a riveting plunger connected with another portion of said lever, said cam adapted to wedge between said lever and guide means, and cause movement of said lever, other sliding cam means adapted to ride on said guide means, other lever means having one portion adjacent to said guide means, a vise means for holding work to be acted upon by said riveting plunger, and movable jaws therefor engageable with said other lever means, said other sliding cam means adapted to wedge between said guide means and said other lever means, and cause movement of said other lever means, so as to actuate said movable vise jaws, said vise jaw actuating means comprising said vise, cam and lever means constructed so as to bring said vise means into action before said riveting plunger is brought into action.

10. In a riveting machine, a cylinder, a piston slidably mounted therein, a cam connected with the said piston, guide means for said cam, a lever, one portion thereof adjacent to said guide means, a riveting plunger connected with another portion of said lever, said cam adapted to wedge between said lever and guide means, and cause movement of said lever, other sliding cam means adapted to ride on said guide means, other lever means having one portion adjacent to said guide means, a vise means for holding work to be acted upon by said riveting plunger, and movable jaws therefor engageable with said other lever means, said other sliding cam means adapted to wedge between said guide means and said other lever means, and cause movement of said other lever means, so as to actuate said movable vise jaws, said vise jaw actuating means comprising said vise, cam and lever means constructed so as to bring said vise means into action before said riveting plunger is brought into action, and resilient means for absorbing excess movement of said vise actuating means after said vise means has clamped the work.

11. In a riveting machine, a cylinder, a

piston slidably mounted therein, a cam connected with the said piston, guide means for said cam, a lever, one portion thereof adjacent to said guide means, a riveting plunger connected with another portion of said lever, said cam adapted to wedge between said lever and guide means, and cause movement of said lever, other sliding cam means adapted to ride on said guide means, other lever means having one portion adjacent to said guide means, and cause movement of said other lever means, so as to actuate said movable vise jaws, said vise jaw actuating means comprising said vise, cam and lever means constructed so as to bring said vise means into action before said riveting plunger is brought into action, said riveting plunger operating cam shaped so that the force delivered to said riveting plunger is increased as said plunger is brought into action, until when it is in actual engagement with a rivet, sufficient force is developed to enable said riveting plunger to shape said rivet by a pressing action.

12. In a riveting machine, a die, a plunger movable into engagement therewith, a vise means including a movable jaw, a jaw actuating means, a plunger actuating means, a cam including a portion engageable with said jaw actuating means for causing a rapid initial movement thereof, and a portion engageable with said plunger operating means formed to cause a retarded movement of said plunger relative to said jaw movement, and means for shifting said cam into engagement with said jaw and plunger actuating means.

In testimony whereof, I have hereunto set my hand at San Diego, California, this 24th day of May, 1929.

FREDERICK H. ROHR.
